UNITED STATES PATENT OFFICE.

ELIZABETH FERGUSON HUME, OF DUNEDIN, NEW ZEALAND.

CORSET.

1,214,467.

Specification of Letters Patent. Patented Jan. 30, 1917.

Application filed August 12, 1913. Serial No. 784,418.

To all whom it may concern:

Be it known that I, ELIZABETH FERGUSON HUME, spinster, a subject of King George V of Great Britain, residing at 40 Dowling street, Dunedin, in the Dominion of New Zealand, have invented certain new and useful Improvements in Corsets, of which the following is a specification.

This invention relates to garments used by women for the support of the body.

It is common in the manufacture of corsets to make each section from a number of longitudinal strips and to impart the desired fullness at different portions by the use of strips of varying widths, and also by the employment of intermediate gore-pieces or darts shorter than the strips, having edges more or less curved.

My invention consists in means for avoiding the objections incident to the ordinary methods of manufacture, and is designed to improve the shape of the corset by the introduction of sections of special shape whereby the figure may be improved and have the desired support where it is most needed without undue pressure.

In order that the invention may be clearly understood I make reference to the accompanying sheets of drawings, in which:—

Figure 1 is a front view of the corset. Fig. 2 is a side view. Fig. 3 is a rear view. Fig. 4 is a view showing the separate sections from which the corset is constructed.

The invention comprises the employment of several sections numbered 1 to 9, shown plainly in Fig. 4. There may be nine more or less in each half of the corset, according to the size of the figure. The first section (1) is narrow at the top (1^a) and wide at the bottom (1^b), the second section (2) is wide at the top (2^a) and narrow at the bottom (2^b) and so on to the completion of the corset, with the exception of the last section (9) which is approximately of uniform width. The sections are attached to one another, and are so arranged that the narrow end (1^a) of the first section (1) is at the top of the corset, and the narrow end (2^a) of the second section (2) is at the bottom of the corset; the succeeding sections are arranged in like manner and attached, each alternate one having its narrow end at the top, so as to give the desired fullness in the corset where required. Above the waist line (10) of Fig. 4, the fullness referred to is directed toward the front by reason of each section be-

ing united to its adjoining section in an inverted form, alternately narrow and wide at the top and bottom, while the fullness below the waist line is directed toward the back. This construction gives the desired support to the bust and abdomen.

In the corset made according to this invention, the joints (11), (12), (13), (14), (15), (16), (17), (18), uniting each section would appear consecutively, the first joint (11) at an angle, the second (12) straight, the third (13) at an angle, the fourth (14) straight, and so on from the front of the corset, section (1) to section (8) on both sides. Section (9) has a particular shape of its own, it is straight from the waist line (10) up and from the waist line (10) down, forming an angle, the longitudinal edges of said section being approximately parallel; the object of having section (9) an angular section is to provide a straight joint at the center back when the corset is being worn and fitting the contour of the body, so that when the two parts are laced together they will be capable of being drawn together without twisting the metal pieces usually attached to this section. In this construction also the stiffeners or bones are less liable to break, the corset strengthened and its shape maintained.

What I claim as new and desire to secure by Letters Patent is:—

A corset composed of two similar members each of which comprises a plurality of sections, the upper extremity of the first front section of each member above the waist line thereof being narrower than the lower extremity of the same section and the second section having an upper wide extremity and a lower narrower extremity, and so on alternately throughout the whole series of sections toward the back of the member except the last section at the back which has both the upper and lower extremities thereof of the same width, the upper portion of the last section at the back having its body vertically straight from the waist line upwardly and angularly disposed relatively to the upper part thereof from the waist line downwardly, the sections increasing in length from the front to the rear section, the joints between the first and second sections being at an angle and straight between the second and third sections, and so on alternately throughout the series of sections, whereby the fullness of the corset above the waist line relatively to a vertical plane coincident with

the back above the waist line is directed to the front and the fullness of the corset below the waist line relatively to the same plane is directed toward the rear of the corset when 5 the latter is applied to the body of the wearer.

In testimony whereof I have hereunto set

my hand in presence of two subscribing witnesses.

ELIZABETH FERGUSON HUME.
